UNITED STATES PATENT OFFICE

152,027

DESIGN FOR A COSMETIC CONTAINER

Pearl L. Schluttig, Kansas City, Mo.

Application November 19, 1946, Serial No. 134,889

Term of patent 7 years

(Cl. D58—8)

To all whom it may concern:

Be it known that I, Pearl L. Schluttig, a citizen of the United States, residing at Kansas City, in the county of Jackson and State of Missouri, have invented a new, original, and ornamental Design for Cosmetic Containers, of which the following is a specification, reference being had to the accompanying drawing, forming part thereof.

Fig. 1 is a top plan view;

Fig. 2 is a front elevation showing my new design for a cosmetic container; and

Fig. 3 is a bottom plan view.

I claim:

The ornamental design for a cosmetic container, as shown.

PEARL L. SCHLUTTIG.
